ROTOR COMPRISING PIVOTED HAMMER PROVIDED WITH ARMORED OUTER PORTION AND PLATE-SHIELDED INNER PORTION

Wayne C. Rogers, Worcester, Mass., assignor to Riley Stoker Corporation, Worcester, Mass., a corporation of Massachusetts

Application November 1, 1950, Serial No. 193,431

5 Claims. (Cl. 241—197)

1

This invention relates to hammer mills, and more particularly to apparatus of the type having a rotor with a series of hammers secured to its periphery, these hammers being arranged to strike pieces of material (for example coal) and thereby crush the same.

With such mills as heretofore constructed the hammers have been subjected to very severe conditions. The material being crushed often causes these parts to wear away rapidly by the effect of impact and abrasion. Any hard foreign bodies, such as pieces of tramp metal which may be mingled with the material, produce shocks and often result in breakage of the hammers. Attempts to solve these problems by selection of a suitable material for the hammers have not been particularly successful. In general, materials tough enough to withstand heavy shocks wear away too rapidly from the abrasive action, whereas materials hard enough to withstand abrasion are too brittle and will be broken when tramp metal enters the machine.

It is accordingly one object of the invention to provide a comparatively simple and inexpensive hammer mill capable of operation for very long periods of service without the need for repair.

It is a further object of the invention to provide an improved construction for the revoluble hammers of a hammer mill, whereby these parts will be capable of withstanding heavy shocks without breaking, and severe abrasive conditions without appreciable wear.

With these and other objects in view, as will be apparent to those skilled in the art, the invention resides in the combination of parts set forth in the specification and covered by the claims appended hereto.

In accordance with the invention there is provided a rotor with a series of hammers secured to its periphery. The rotor may be in the form of a disk, and each hammer comprises an outer portion or head having a flat front surface and an inner supporting portion fastened to the disk. A protective armor of extremely hard material is secured to the front surface of the head, and a separate shield is mounted in front of the supporting portion. The supporting portion of each hammer preferably includes two laterally spaced apertured ears, and each shield preferably comprises a plate having two laterally spaced apertured ears extending rearwardly therefrom. A single pin or the like preferably extends through the ears of each hammer and the ears of the corresponding shield to provide a pivotal connection between these parts and the rotor disk.

2

Referring to the drawings illustrating one embodiment of the invention, and in which like reference numerals indicate like parts,

Fig. 1 is a vertical section through a hammer mill, the section being taken on the line 1—1 of Fig. 2;

Fig. 2 is a section taken on the line 2—2 of Fig. 1;

Fig. 3 is a fragmentary side elevation of a rotor and associated parts;

Fig. 4 is a front elevation of a hammer;

Fig. 5 is a side elevation of a hammer;

Fig. 6 is a side elevation of a shield; and

Fig. 7 is a rear elevation of a shield.

The embodiment illustrated in Fig. 1 comprises a housing 10 having an upper entrance opening 11 for the coarse material, a lower discharge opening 12 for the crushed material, and a collecting pocket 14 for tramp metal or other non-crushable material. A horizontal rotatable shaft 15 extends through the housing, and on this shaft there is mounted a vertical rotor disk 16 with a series of hammers 18 secured to its periphery. An arcuate grid or screen 19 is mounted within the housing 10 beneath the rotor disk and spaced slightly from the outer ends of the hammers. As shown in Fig. 2, there are preferably two of the disks 16, axially spaced from one another and each carrying a separate series of hammers.

Referring particularly to Figs. 4 and 5, each hammer 18 comprises a generally rectangular outer portion or head 21 having a flat front surface 22, and an inner supporting portion 23 including two laterally spaced apertured ears 24, these parts preferably being made of a strong tough material such as steel. The front surface 22 is protected by suitable armor plate 26. This armor plate comprises eight flat rectangular pieces of an extremely hard material, preferably tungsten carbide, although other hard materials can be employed. The armor plate may be secured to the surface 22 by silver soldering or brazing. As shown in Fig. 2, the spaced ears 24 straddle the peripheral portions of the rotor disks 16 at assembly, and each pair of laterally adjacent hammers is pivotally attached to the disks by a pin 27 which extends through the ears and the disks. Preferably the disks are provided with outwardly projecting circumferentially spaced apertured lugs 28 through which the pins 27 extend.

A separate device is associated with each hammer 18 to protect the inner supporting portion 23 thereof from abrasion and wear. For this purpose a flat rectangular plate or shield 29 is

mounted in front of the portion 23, the plate having two laterally spaced apertured ears 30 extending rearwardly therefrom. These parts are preferably formed of manganese steel or a similar tough hard material capable of resisting abrasion. The ears 30 are spaced apart somewhat farther than the hammer ears 24 so that they may straddle the hammer ears at assembly, as shown in Fig. 2, and the pin 27 may extend through both sets of ears. In order to hold the pin 27 in place, a sleeve 32 is mounted on the central portion of the pin between the adjacent ears 30, and a cotter pin 33 extends diametrically through this sleeve and the pin 27. The outer edge of the shield plate 29 slightly overlaps the armor plate 26.

The operation of the invention will now be apparent from the above disclosure. Coarse material will be fed through the opening 11 into the housing 10, and this material will be struck by the revolving hammers 18 and thereby crushed sufficiently to pass downwardly through the grid 19 and the discharge passage 12. Any large pieces of tramp metal or other uncrushable material will be thrown into the pocket 14 in known manner. The armor plate 26 will protect the heads 21 of the hammers from abrasion, while the heads will provide the weight, strength and toughness required to support the armor plate properly and ensure the desired crushing action. While practically all of the crushing will be brought about by the engagement of the armored heads 21 with the material, there will nevertheless be an appreciable cloud of dust located inwardly of these heads. The shields 29 will protect the inner supporting portions 23 of the hammers from the abrasive action of this dust cloud. Thus the hammers 18 will have an extremely long life of useful service. In ordinary operation, centrifugal force will hold the hammers and shields in the substantially radial positions shown in Fig. 3, but if a large heavy piece of tramp metal should enter the machine these parts are free to swing rearwardly about the pins 27 and into the spaces between the lugs 28, as indicated by the broken lines.

Having thus described my invention, what I claim as new and desire to secure by Letters Patent is:

1. A hammer mill comprising a rotor disk, a series of hammers spaced around the periphery of the disk, each hammer including an outer portion or head having a flat front surface and an inner supporting portion having two laterally spaced apertured ears which straddle the adjacent portion of the disk, a protective armor of extremely hard material secured to the front surface of each hammer head, a separate shield plate located in front of the inner portion of each hammer to protect the same from abrasion, two laterally spaced apertured ears on each shield plate and straddling the adjacent portion of the disk, and a pin or the like extending through the hammer ears, the shield plate ears, and the disk,

2. A hammer mill comprising a rotor disk shaped to provide a series of circumferentially spaced and outwardly projecting apertured lugs, a series of hammers spaced around the disk adjacent the respective lugs, each hammer including an outer portion or head having a flat front surface and an inner supporting portion having two laterally spaced apertured ears which straddle the adjacent lug, a protective armor of extremely hard material secured to the front surface of each hammer head, a separate shield plate located in front of the inner portion of each hammer to protect the same from abrasion, two laterally spaced apertured ears extending rearwardly from each shield plate and straddling the adjacent lug, and a pin or the like extending through each lug, the adjacent hammer ears, and the adjacent shield plate ears.

3. A hammer mill as set forth in claim 2 in which the shield plate ears are spaced farther apart than the hammer ears so as to straddle the same.

4. A hammer mill comprising a rotor, a series of hammers spaced around the periphery of the disk, each hammer being pivotally mounted on the rotor, each hammer including an outer portion having an impact surface and an inner portion by which it is mounted on the rotor, a protective armor of extremely hard material secured to the impact surface of each hammer, a separate shield plate mounted in front of the inner portion of each hammer to protect the same from abrasion, each said shield plate being mounted on a common pivotal axis with its respective hammer.

5. A hammer mill comprising a rotor, a hammer, a shield plate, said hammer being pivotally mounted on the rotor, said hammer having an outer portion having an impact surface and an inner portion by which it is mounted on the rotor, and a protective armor of extremely hard material secured to the impact surface of said hammer, said shield plate being pivotally mounted on said rotor immediately adjacent the hammer and being situated in front of the inner portion of the hammer to protect the same from abrasion, the hammer and the shield plate being mounted on a common pivotal axis.
